CLAIM

The ornamental design for an electric dry shaver with cover, as shown and described.

DESCRIPTION

FIG. 1 is a front, top and left-side perspective view of an electric dry shaver with cover showing our new design with the cover in place;

FIG. 2 is a rear, bottom, and right-side perspective view with the cover in place;

FIG. 3 is an exploded perspective view similar to FIG. 1 with the cover separated from the shaver;

FIG. 4 is an exploded perspective view similar to FIG. 2 with the cover separated from the shaver;

FIG. 5 is a rear elevational view of the shaver;

FIG. 6 is a front elevational view of the shaver;

FIG. 7 is a left-side elevational view of the shaver;

FIG. 8 is a right-side elevational view of the shaver;

FIG. 9 is a top plan view of the shaver;

FIG. 10 is a bottom plan view of the shaver;

FIG. 11 is a right-side elevational view of the cover;

FIG. 12 is a left-side elevational view similar to FIG. 7 with the socket rotated downwardly;

FIG. 13 is a rear elevational view similar to FIG. 5 with the socket rotated downwardly; and

FIG. 14 is a bottom plan view similar to FIG. 10 with the socket rotated downwardly.
